UNITED STATES PATENT OFFICE.

MAX W. ZABEL, OF CHICAGO, ILLINOIS.

SIGNALING SYSTEM FOR RAILROADS.

No. 892,203.

Specification of Letters Patent.

Patented June 30, 1908.

Application filed April 13, 1907. Serial No. 368,025.

To all whom it may concern:

Be it known that I, MAX W. ZABEL, a citizen of the United States, residing at Chicago, in the county of Cook and State of Illinois, have invented a certain new and useful Improvement in Signaling Systems for Railroads, of which the following is a full, clear, concise, and exact description, reference being had to the accompanying drawings, forming a part of this specification.

My invention relates to signaling systems for railroads and has for its object the provision of an improved system whereby any block in a train despatcher's division may receive a selective signal to the exclusion of all other blocks in the same section, and means whereby positive indication is given to the train despatcher or operator that the selective signal which is set is properly received; or for instance, if the system is applied to signals which can be set or released from the train despatcher's office, my system contemplates the provision of an improved device whereby positive indication is received at the sending station that the signal has been set or released, which indication is sent by some operating portion of the signal itself or its associated mechanism.

I have shown in a co-pending application Serial No. 368,026, filed April 13, 1907, a selective signaling system whereby signals can be selectively set or released along a railroad right-of-way, and I have shown my present invention of signaling back as applied to this particular system of selective signaling, I will describe my invention more in detail in connection with the accompanying drawing illustrating one embodiment thereof.

I have shown in the drawing, rails *a b* which indicate a complete train despatcher's division which we can assume in this case for instance to be 80 miles long, and this division is divided into eight separate blocks preferably between stations and each block is provided with a signal suitably placed, which signals I have numbered *c d e f g h i* and *k*. In my improved system each one of these signals *c d e*, etc. can be operated without any of the remaining signals, thus to set the danger signal in the block, or to release said danger signal, and in case it is found necessary to provide more than one signal for each block as it undoubtedly will be, a plurality of signals can be provided in each block along the right-of-way, so that at any point in said right-of-way a danger signal is visible if the particular

master signal *c d e*, etc. is set at danger or "clear". This is described in my co-pending application.

I will describe briefly the operation of the signal *k* when the relay 1 of this station *k* is operated. It closes a circuit from the battery *w* through coils 2 2 of an operating motor 3, through line wire 4, relay 5, contact 6, spring 7, spring 8, back to the free pole of battery *w*. This starts the operation of the motor 3 which draws the target 9 into place and sets it at danger. While this is going on relay 5 has closed its armature 10 and current flows from the battery *w* through coils 2 2 of the motor, relay 5, through the armature 10 of said relay and its associated contact up to free pole of battery *w*, thus closing the battery circuit on the motor 3 and keeping the target 9 in its operated position. At the same time also spring 7 comes into contact with spring 11 and changes the circuit conditions. The reason for this is that relay 1 having just received one impulse is allowed to go back to its normal position, the target 9 having operated. Now then a second impulse of the relay 1 will again close the armature against its contact 6 and by reason of the changed circuit conditions of the springs 7 and 11 a short circuit is now provided around the relay 5 which short circuit can be traced from the armature 10 to the contact 6 and its associated armature to spring 7, and spring 11 back to the other side of the relay 5 thus allowing this relay to fall back when the armature of relay 6 falls back, thus breaking the battery current and allowing the target 9 to fall down and again assume its clear position.

The operation of the targets thus depends upon the successive impulses of the relays 1, one of which is provided for each signal station. To operate the relay 1 selectively any suitable system can be employed, the system prefer to use, however, being the same as described in my co-pending application and the operation of which consists essentially in providing a relay 12 at each signal station in connection with a relay 1, which relay 12 and relay 1 are suitably connected to line wires *m* and *n*. I provide two sets of batteries *o* and *p* which batteries can furnish negative and positive continuous current as required. Also a generator *q* which can furnish alternating current. The relay 1 operates with the alternating current, and the relays 12 operate with direct current. The relays 12

are so arranged that they are responsive selectively to negative battery current or positive battery current. It is obvious that by connecting either positive or negative battery current to either line wire m or n , two relays 12 will always operate, thus getting a selection of two stations. To get a selection of the proper station of these two which are operated by battery current, I connect the relays 1 at these particular two stations under consideration, so that one relay 1 is connected between wire m and ground, and the other relay 1 is connected between line wire n and ground. Then I use alternating current in conjunction with the battery current to selectively operate either one of the relays 1 which are connected between the different line conductors and ground, thus a selection of either of the eight is obtained. The relays 12 of course are connected between either line wire m and n to ground. In some cases it is apparent both alternating current and continuous current will be on the line wires m and n at the same time, and in that case it is not necessary to use the generator g , because the resultant current of the alternating generator and the battery will be in the nature of a pulsating current, which I prefer to furnish through an interrupter r , which gives either pulsating positive or pulsating negative current. Suitable condensers x are provided to prevent direct current from going through the relays 1 and suitable impedance coils y are provided to prevent the objectionable passage of alternating current through the relays 12.

Suitable spring combinations, eight in number, are provided which correspond respectively to each sub-station and which are preferably mounted in the form of one ringing key s . By operating either one of the spring combinations the desired one of the signals c , d , e , etc. is operated without operating any other. This manner of signaling is more fully described in my co-pending application, but it is thought this explanation will be clear. To make the selection of these signals effective, it is necessary to provide suitable means whereby positive indication is given to the sender, or operator of the spring mechanisms s that the particular signal which he is operating is actually performing its allotted function. To provide this result, I employ preferably on the movable part of the motor 3 or its associated mechanism, a contact plate 13, this contact plate 13 is different in the different stations c , d , e , and f , in that it is provided with teeth corresponding to its particular station. Thus contact plate 13 at station c has one tooth, contact 13 at station d has two teeth and so on up to station k whether the contact plate 13 has eight teeth. I connect this contact plate 13 with one pole in this case negative of the battery w , and the positive pole of this

battery to the line wire n . I provide a spring contact 14 which is connected to the other line wire m .

Now when the motor 3 begins to operate, which will be after an impulse has been sent over the relay 1, the contact plate 13 will be brought successively into association through its teeth with the spring 14 and send successive impulses from the battery w over the line wires m and n which impulses correspond in number or form to the particular station from which they are sent, thus sending a selective indication back to the center that the chosen signal is performing its function. In this way a test can be made every day to see that all mechanism is in operating form without going over the various signals distributed along the extensive right-of-way. To properly give these selective return indications to the operator at the central station who manipulates the spring combinations s , I provide a relay t which is connected across the line wires m and n , through an impedance coil u which relay closes a battery circuit through a sounder v , and which sounder registers the number of impulses sent up from the operating signal thereby to give positive indication of the proper performance of its function by said signal. Of course other suitable means may be provided for registering or suitably indicating the return indications of these various signals.

I have herein shown what appears to be the most simple form which my invention may take, and while I have herein shown and particularly described the preferred embodiment of my invention, I do not wish to limit myself to the precise construction and arrangement as herein set forth, but

Having thus described the preferred embodiment thereof what I claim as new and desire to secure by Letters Patent is:

1. A signaling system for railways comprising a signal sending station, a plurality of signals distributed along the right-of-way of a railroad track, electro magnetic means associated with each signal for operating same, circuit changing devices in connection with apparatus for supplying currents of different electrical character at the sending station for causing the operation of any desired electro magnetic means to the exclusion of the remaining said means to operate the signals, and electro magnetic means for receiving a return indication from the operating signals.

2. A signaling system for railways comprising a signal sending station, a plurality of signals distributed along the right-of-way of a railroad track, an electro magnetic device to control the operation of each signal, means at the signal sending station including currents of different electrical character to operate the desired electro magnetic device of a predetermined signal, switching devices

at the sending station for supplying currents to control the reverse operation of the said pre-determined signal, and an electric device at the signal sending station for receiving a return indication from the operating signals.

3. A signaling system for railways comprising a signal sending station, a plurality of signals distributed along the right-of-way of a railroad track, an electro magnetic device to control the operation of each signal, means at the signal sending station including currents of different electrical character to operate the desired electro magnetic device of a pre-determined signal, switching apparatus at the sending station for supplying current to control the reverse operation of said predetermined signal, and an electric device at the signal sending station for receiving a selective return indication from the operating signals.

4. A signaling system for railways comprising a signal sending station, a plurality of signals distributed along the right-of-way

of a railroad track, an electro magnetic device to control the operation of each of the 25 said signals, switching apparatus associated with each device whereby one operation of said device will cause the movement of its associated signal in one direction and a second operation of said device will cause the 30 operation of its associated signal in a different manner, means at the signal sending station including currents of different electrical character to cause the desired operation of the electro magnetic device at any 35 pre-determined signal, and electro magnetic appliances at the signal sending station for receiving a selective return indication from the operating signals.

In witness whereof, I hereunto subscribe 40 my name this sixth day of April, A. D: 1907.

MAX W. ZABEL.
